[57] CLAIM

The ornamental design for a sports container carrier, as shown and described.

DESCRIPTION

FIG. 1 is a front, top and right side perspective view of a sports container carrier showing my new design, the broken line disclosure of the top portion of the container being for illustrating purposes only and forming no part of the claimed design;

FIG. 2 is a top plan view thereof;

FIG. 3 is a bottom plan view thereof;

FIG. 4 is a front elevation view thereof;

FIG. 5 is a rear elevation view thereof;

FIG. 6 is a left side elevation view thereof; and,

FIG. 7 is a right side elevation view thereof.
